UNITED STATES PATENT OFFICE.

EUGENE N. PHILLIPS, OF SAN ANTONIO, TEXAS, AND HARVEY H. DICK, OF CHICAGO, ILLINOIS, ASSIGNORS TO AMERICAN STEAM BOILER CLEANER CO., OF SAN ANTONIO, TEXAS, A CORPORATION OF TEXAS.

BOILER-SKIMMER.

1,318,912.

Specification of Letters Patent.

Patented Oct. 14, 1919.

Application filed October 16, 1918. Serial No. 258,374.

To all whom it may concern:

Be it known that we, EUGENE N. PHILLIPS and HARVEY H. DICK, citizens of the United States, residing at San Antonio and Chicago, respectively, in the counties of Bexar and Cook, respectively, and States of Texas and Illinois, respectively, have invented certain new and useful Improvements in Boiler-Skimmers, of which the following is

10 a specification.

This invention relates to boiler cleaners or skimmers of the type disclosed in an application filed by us May 9, 1917, Serial No. 167,549, the objects of the present invention 15 being to improve the hinge joint so that the water or scum will have free access therethrough in all positions of the skimmer, to improve the mounting of the floats, and to increase the inlets for the scum.

20 The invention is illustrated in the accompanying drawings, in which—

Figure 1 is an elevation of the skimmer showing the position of the same within a locomotive;

25 Fig. 2 is an end view of the skimmer with the dry pipe of the locomotive in section;

Fig. 3 is a plan view of the skimmer with parts in section;

30 Fig. 4 is an enlarged side elevation of the skimmer;

Fig. 5 is a section through the lower hinge joint on the line 5—5 of Fig. 3;

Fig. 6 is a transverse section on the line 6—6 of Fig. 5.

35 The locomotive may be of any well-known type and is illustrated in a conventional dia-

grammatical manner only. The dry pipe 1 is supported in the steam space of the loco-

40 motive boiler in the usual or any preferred manner and upon the said pipe we secure

yokes or bridge plates 2 by means of U-

shaped clamping bolts 3, the ends of the

45 yokes 2 being provided with sleeve members

4 to clamp and support the side tube por-

50 tions 5 of the skimmer. The side tubes 5

constitute parts of the supporting frame

and their upper ends are connected by trans-

55 verse pipes or tubes 6, these in turn being

connected by a central longitudinal tube 7

disposed above the dry pipe and equipped

at an intermediate point of its length with a

coupling 8 from which an outlet pipe 9 ex-

10 tends through the top of the boiler. Above

the boiler this pipe 9 extends into a valve cas-

ing 10 and from said casing a discharge pipe 11 extends into the locomotive cab. The discharge pipe 11 enters a valve casing 12 from which a drain pipe 13 depends and a branch 14 leads from the said drain pipe and is normally open, the flow being controlled by a valve 15 disposed at the junction of the drain pipe 13 and the branch. A supplemental drain 16 is also connected to the drain pipe 13 and is equipped with a cut-off valve 17. Normally there is a constant flow 15 of scum through the pipes 11, 13 and 14 which is controlled by the valve 15 and the valves in the casings 10 and 12. Should the scum accumulate so as to necessitate a more rapid or vigorous discharge of the same, 20 the valve 15 is closed and the valve 17 opened, whereupon the accumulation will be rapidly discharged through the drain pipe 16. The yokes 2 are, of course, disposed in spaced relation upon the dry pipe and they 25 are maintained in this relation by connecting rods 18 which have their ends secured rigidly in the yokes at the outer sides of the bolts 3 and extend between the yokes, as clearly shown.

At the sides of the dry pipe and the yokes, we dispose skimmer pipes 19 and 20 which are arranged in pairs at the two sides of the mechanism, as shown most clearly in Fig. 3. The pipes 19 and 20 are each provided with 30 slots or openings 21 in their sides to permit the scum collecting upon the surface of the water to enter the skimmer pipes and a float 22 is disposed between the skimmer pipes 19 of each pair of pipes to maintain the pipes 35 at the surface of the water. The pipes 19 are connected at their ends by branch tubes 23 with the collars or rings 24 fitted concentrically around the ends of the respectively adjacent pipe 20 and said collars 24 provide 40 a common outlet for the pipes 19 and 20. The collar 24 may be formed integral with or rigidly secured to a sleeve or coupling member 25 which constitutes one member of a hinge joint whereby the skimmer pipes are 45 connected to the upper ends of normally inclined conveyer tubes 26. The coacting member of the hinge joint has a tubular or cylindrical body 27 secured rigidly upon the upper end of the tube 26 and communicating 50 therewith. The tubular or cylindrical bodies 25 and 27 are connected so as to be capable of relative rotary movement and be

prevented from relative endwise movement, while at the same time furnishing a water-tight joint. The lower end of the tube 26 is fitted in a radial nipple or boss 28 on a tubular casing or hub 29 which hub or casing fits rotatably upon the lateral hub member 30 of an elbow coupling 31 secured upon the lower end of the frame member 5. The said coupling 31 is provided with an annular shoulder 32 against which the inner edge or end of the hub 29 engages and the said hub is held rotatably upon the bearing 30 by a cap plate 33 which is threaded into the end of the bearing and fits against the outer edge or end of the hub. The bearing 30 is, of course, tubular and in the wall of the same are provided openings 34 which may be of any preferred configuration and form a constantly open source of communication between the hollow interior of the hub or casing 29 and the bore of the elbow 31 as will be readily understood on reference to Figs. 5 and 6. The hub or casing 29 is provided with a second boss 35 disposed in angular relation to the boss 28 and adapted to receive and carry an extended counter-weight 36, the counterweight being provided on its inner side with a stop lug or projection 37 adapted to impinge against the side frame member 5 in the operation of the skimmer and thereby limit the downward movement of the skimmer pipes and the float.

The float 22 is preferably a hollow cylinder having closed ends and secured to and between brackets 38 which are secured upon the ends of the inner skimmer pipes 20 immediately adjacent the coupling tubes 23 which connect the outer and inner skimmer pipes, as clearly shown in Fig. 3. By this arrangement we are enabled to use long floats which may be very quickly assembled with the other parts of the mechanism and which will impart a high degree of buoyancy to the apparatus so that the skimmer pipes 45 will be maintained at the level of the water in the boiler under all conditions and will not be easily submerged.

It is thought the operation of the device will be readily understood. The floats serve to normally retain the skimmer pipes at the level of the water in the boiler and the counterweights 36 serve to balance the weight of the skimmer pipes and the connecting tubes 26 so that the floats will very quickly return to the normal position after any shifting due to a change in the level of the locomotive and will also promptly respond to variations in the water level. By providing two skimmer pipes at each side of the apparatus the capacity of the device is increased and the scum more rapidly withdrawn while the skimmer pipes also serve to guard the floats against possible injury due to any tendency of the floats to sway against the sides of the supporting frame under

violent agitation of the water. It will be noted particularly upon reference to Figs. 5 and 6 that the wall of the lateral bearing portion of the elbow 31 is reduced between the ends of said lateral bearing portion and, consequently, there is a continuous uninterrupted constantly open space between the hub or casing 29 and the bearing so that the access of the scum and impurities to the side members 5 of the frame and outlet is free at all times and in all positions of the skimmer. The apparatus is exceedingly simple and compact in the construction and arrangement of the parts and is highly efficient in operation.

Having thus described our invention, what is claimed as new is:

1. In an apparatus for the purpose set forth, the combination of a tubular supporting frame, an outlet leading from said frame, pairs of skimmer pipes disposed at the sides of said frame, floats carried by and between the skimmer pipes of each pair, conveyer tubes leading from the skimmer pipes to the sides of the tubular supporting frame, hinge joints between the skimmer pipes and the upper ends of the said conveyer tubes, hinge joints between the sides of the supporting frame and counterweights connected with said tubes. 95

2. In an apparatus for the purpose set forth, the combination of a tubular supporting frame, an outlet leading from said frame, pairs of skimmer pipes disposed at the sides of said frame, floats carried by and between the skimmer pipes of each pair, conveyer tubes leading from the skimmer pipes to the sides of the tubular supporting frame, hinge joints between the skimmer pipes and the upper ends of the said conveyer tubes, hinge joints between the sides of the supporting frame and counterweights connected with said tubes, said counterweights being provided with lateral stops on their inner sides to engage against the sides of the supporting frame. 105

3. In an apparatus for the purpose set forth, the combination of a tubular supporting frame, an outlet leading from said frame, conveyer tubes having hinged connections with the sides of the supporting frame, pairs of skimmer pipes the pipes of each pair having common hinged connection with the upper ends of said conveyer tubes, and floats disposed between the pipes of each pair of skimmer pipes and supported by the inner of said pipes adjacent the hinge connection of the same with the upper end of the conveyer tube. 125

4. In an apparatus for the purpose set forth, the combination of a tubular supporting frame having vertically disposed side members, elbows at the lower ends of said side members having the walls of their 130

lateral portions reduced between the ends thereof and provided with openings therethrough, skimmer pipes, conveyer tubes having hinged connections at their upper ends with the skimmer pipes, hub members carried by the lower ends of said conveyer tubes and rotatably fitting over the lateral bearing members of the elbows, and means for retaining said hubs upon the said bearing members.

5. In an apparatus for the purpose set forth, the combination of a tubular frame member, an elbow at the lower end of said member having an annular exterior shoulder at the inner end of its lateral bearing member, the wall of said member being re-

duced exteriorly between its ends and having openings formed therethrough, a skimmer pipe, a conveyer tube having hinged connection at its upper end with the skimmer pipe, a hub carried by and communicating with the lower end of said conveyer tube and fitting rotatably around the lateral bearing member of the elbow with its inner edge against the annular shoulder on 20 said elbow, and a cap plate secured in the end of the elbow and bearing against the outer edge of said hub.

In testimony whereof we affix our signatures.
